UNITED STATES PATENT OFFICE.

LESLIE W. CLAYBOURN, OF MILWAUKEE, WISCONSIN.

MEANS FOR COMPRESSING PRINTING PLATES.

Original application filed March 19, 1921, Serial No. 453,665. Divided and this application filed December 7, 1922. Serial No. 605,455.

To all whom it may concern:

Be it known that I, LESLIE W. CLAYBOURN, a citizen of the United States, residing at Milwaukee, in the county of Milwaukee and 5 State of Wisconsin, have invented certain new and useful Improvements in Means for Compressing Printing Plates, of which the following is a specification.

My present application is a division of an 10 application heretofore filed by me in the United States Patent Office March 19, 1921, as Serial No. 453,665, for method of correcting printing plates and printing plates produced thereby.

15 I do not herein claim the method of correcting printing plates, or the method of compressing printing plates, or the printing plates produced thereby, herein shown and described, having shown, described and 20 claimed the same in my aforesaid prior application, Serial No. 453,665.

It is the object of my invention to provide new and improved means whereby to minimize or substantially reduce so-called make- 25 ready on the printing press, and I have shown my invention applicable to flat printing plates and also to curved printing plates, although portions of my invention are especially employable in connection with 30 curved printing plates.

It is the object of my invention to provide novel means whereby to bring all portions of the printing surface into the projection of the same surface, that is, into the same plane 35 if the plate be a flat plate, and into the same surface of the sector of a cylinder if the plate be a curved plate; further, to provide new and improved means whereby to compress the backing of a printing plate in 40 order to impart to the same a greater density than when the plate is first formed; further, to provide means whereby to compress a printing plate for correction of its printing surface with pressure per area of surface 45 greater than the printing pressure per area of surface applied to the plate; further, to provide means whereby to cause differential compression of the backing of the printing plate according to the solidities of the various portions of the printing surface of the 50 printing plate; further, to provide means

for compressing the backing of a printing plate with greater density at its solid printing portions than at its high light or light printing portions; further, to provide new 55 and improved means to correct a printing plate by pressing those portions thereof which print with too light an impression toward the printing surface of the printing plate; further, to provide new and improved 60 means whereby to compress the backing of the printing plate while confining said backing as a whole in the plane of said plate; further, to provide new and improved means whereby to compress the backing of a printing plate while maintaining the printing lines in their original printing distance relations in the printing surface and to avoid stretching of its printing surface; further, to provide new and improved means for pressing the sunken or concave printing portions 65 of the printing surface of the printing plate located between printing edges into the plane of said printing edges.

I have found that, when printing plates 75 as heretofore made, the printing surface of the plate will let down or the backing thereof compress in uneven manner away from the proper printing surface to cause imperfect printing. It is a further object of my 80 invention, therefore, to provide means whereby to compress the printing plate and especially the backing material thereof to a density at least as great as any density which might be imparted to the printing 85 plate or its backing by printing pressures, especially at the solid portions of the printing areas.

The invention will be further readily understood from the following description and 90 claims, and from the drawings, in which latter:

Fig. 1 represents a plan view of an exemplifying printing plate.

Fig. 2 is a cross-section of the same taken 95 on the line 2—2 of Fig. 1.

Fig. 3 represents a cross-section of a portion of the printing plate shown in Fig. 1, taken on the line 3—3 of Fig. 1, to illustrate the usual relations between the printing surface and the backing surface in their crude 100 state, as in present methods, the plate being

shown enlarged to disclose imperfections inherent in such plates.

Fig. 4 is a cross-sectional view of the same plate, taken on the same section line as in Fig. 3, the plate being shown subjected to compression by means of an exemplifying compressing member, for compressing the printing plate.

Fig. 5 is a front elevation of an exemplifying machine, partly broken away, for compressing the printing plate.

Fig. 6 is a plan view of one corner of the compressing member, which is exemplified as a compressing member for printing plates having a preponderance of intermediate solidities of printing surface.

Fig. 7 is a plan view of a portion of an exemplifying compressing member for printing plates having a preponderance of solid printing portions.

Fig. 8 is a cross-section of the same, taken on the line 8—8 of Fig. 7.

Fig. 9 is a plan view of a similar compressing member for printing plates having a preponderance of high-lights in the printing surface thereof.

Fig. 10 is a cross-section of the same, taken on the line 10—10 of Fig. 9.

Fig. 11 is a plan view of a portion of an exemplifying compressing member having connected pressing faces.

Fig. 12 is a cross-section of the same, taken on the line 12—12 of Fig. 11.

Fig. 13 is a plan view of the compressed backing of the printing plate illustrated in Fig. 4, partly broken away.

Fig. 14 is a front elevation illustrating an exemplifying machine for compressing a curved printing plate.

Fig. 15 is a side elevation of the same.

Fig. 16 is a vertical cross-section of the same, taken on the line 16—16 of Fig. 15, illustrating the exemplifying means for compressing a curved printing plate.

Fig. 17 is a vertical axial section of the same, taken on the line 17—17 of Fig. 14, partly broken away.

Fig. 18 is a vertical section of a detail of the same, taken on the line 18—18 of Fig. 17.

Fig. 19 is a perspective view of a detail of the same; and,

Fig. 20 is an enlarged view of a sector of a compressing member for compressing a curved plate, taken on the line 16—16 of Fig. 15.

It has heretofore been a usual practice in making ready for the printing from printing plates, to overlay the tympan of the printing press on which the plates are to be printed at those portions at which the printing appears too light in the proofs, or to underlay the printing plate at such portions, or to both overlay and underlay at the insufficiently printing portions, and to cut

the tympan where the printing appears too heavy, with the result that uneven surfaces are obtained both in the tympan and at the bottom of the printing plate, such system making it necessary also to employ a comparatively soft tympan. Other systems have attempted to produce the differences between solid and high-light or light printing effects by locating the high-light or light printing portions of the plate lower than the solid portions, if a flat plate, or nearer the axis of the plate cylinder if a curved plate, this system also producing unevenness of printing surface.

These uneven, waving or undulating surfaces at the rear face of the printing plate, or at the face of the tympan, or both, also, in the course of printing, or during a long run, vary from their original states, especially under the heavy print-pressures necessary to be employed under such old methods, resulting in differences in appearance of the printing during different portions of the run and making subsequent make-readies necessary.

I avoid all these objections by providing means whereby all portions of the printing surface and the printing lines and areas throughout the printing plate are brought into the same projection of a given surface, determined by printing pressure, that is, into the same plane if the plate be a flat plate and into the same surface of the sector of a cylinder if the plate be a curved plate.

I am thereby enabled to produce superior printing, and also to print with a tympan whose impress surface is throughout substantially the projection of the same surface, so that successive printings by different plates or printing elements may be received by the same portions of the tympan, whereby my invention is especially adaptable for preparing printing plates for so-called wet printing, in which successive printings in different colors are printed upon the same sheet during its single passage through the printing press, as well as to all other characters of printing, enhancing the appearance and beauty of the printing and enabling me to reproduce the appearance of solids, high-lights and intermediate printing effects, in highly contrasted relations in the printing from co-ordinated plates representing different colors, and avoiding the humps and hollows in the make-ready for one color which are detrimental to the make-ready for another color in the old methods mentioned, and enhancing true registry of the printing lines.

The term "projection of the same surface", and corresponding expressions throughout the description and claims, are to be understood as meaning "the plane of a flat surface", as applied to a plane surface,

and "the same curved surface of the sector of a cylinder" or "cylindrical surface", as applied to a curved surface. The term is employed for convenience, and avoids confusion in expression where it is desired to describe or claim both or either characters of surface.

Employment of my improved device further enables printing to be accomplished with considerably lighter printing pressures and with harder tympans than under such older methods now in general use and materially increases the numbers of imprints which can be obtained from one make-ready of the printing subject, and by means of my invention, further, the solid portions of the printing plate are compressed to greater extent than the high-light portions of the plate, the density of compression being graduated by or dependent on the comparative solidities of the various printing portions of the printing plate, and printing plates are produced which retain their clarity of printing effect throughout long periods of use.

The projections, that is, the planes or sectors which the printing surfaces or printing lines are caused to occupy by employment of my invention, are intended to be measured by print pressures, as they are ordinarily too refined for observation by the naked eye.

A printing plate is exemplified at 21, and in the present exemplification comprises a printing shell 22, which may be of usual electro-deposited metal, for instance, copper deposited on the matrix in electro-plating, and a backing 23 on which the printing shell is fixedly supported, usually cast into the shell. This backing is usually a composition composed for example of lead, tin and antimony, in the proportion, for example, of ninety pounds of lead and five pounds each of tin and antimony. It is obvious, however, that other backing material may be employed, and that my invention is not limited to means for operating on printing plates thus formed. The printing plate 21 is shown as a flat plate. The printing plate operated on may be a curved plate, as shown at 24. The curved plate is in construction the same as the flat plate, and may comprise a printing shell 22 and a backing 23.

When employing my improved device, the printing plate may at its margins be provided with bearers 25, which may if desired be separated from the printing surface by grooves 26, and the printing plate may also have intermediate or interior bearers, exemplified at 27. The marginal bearers and intermediate bearers may be so associated as to make it advisable to merge the same, as shown at 28.

These bearers are useful for receiving the compressive strains at the edges of the plates, and in intermediate portions of the plate, which would otherwise be devoid of

support in the plane of the printing surface, when employing my improved device. These bearers are removed from the plate in the course of operation on the plate preferably after employment of my improved device thereon, the marginal bearers being removed, as by sawing, and the interior bearers being removed, as by routing, the latter operation leaving spaces in the face of the plate free of printing function. My improved device is, however, employable on plates which are not provided with bearers.

I have in Fig. 1 shown an exemplification of the printing face of a printing plate to be corrected, in this instance by compression, illustrating the differences in solidities of the printing portions of a printing plate, and its bearers. In this exemplification the part 31 represents a solid portion, the parts 32 intermediate portions, and the parts 33 high-light or light portions of the printing surface.

One of the characters of printing plates upon which my present invention is employable, is shown, described and claimed in Letters Patent No. 1,317,967, granted me October 14, 1919, for method of curving printing plates and printing plates curved thereby.

The printing plate may, before being compressed by my improved device, have its back or rear face shaved. Shaving of the back of the printing plate may be accomplished by any usual means, or, for instance, by a shaving machine of the character of that shown, described and claimed in Letters Patent No. 1,282,013, granted me October 15, 1918, for method of and apparatus for shaving printing plates, it being assumed that such shaving machine having a flat bed and linear shaving movement between the shaving elements and the printing plate be employed, when operating on a flat plate, and that such shaving machine having a concavely curved bed and rotary shaving movement be employed when shaving a curved plate.

The printing plate in its original condition is of approximate uniform density throughout, this density of backing material being exemplified by the uniform spacing of the lines representing the cross-sectioning of the printing plate in Figs. 2 and 3.

When the printing plate is first formed, its printing surface, that is to say, the printing lines of the printing surface, are wavy in portions, or the portions of the printing surface are not in the projection of the same surface, that is, in the same plane if the printing plate be a flat plate, or the same surface of a cylinder if the printing plate be a curved plate. The printing plate, when first formed, or when reduced to approximate uniform thickness throughout at its printing lines, by shaving its rear face, has,

as a matter of fact and in printing effect, undesirable irregularities in its printing surface and in thicknesses in different portions of the plate, forming undue high or 5 low places in the printing surface, resulting in imperfect printing impressions and the practice heretofore of overlaying the tympan or underlaying the plate or the block on which the plate is mounted.

10 In my improved device, I compress the backing of the printing plate, and solidify any soft or porous spots in the printing plate, and press all portions of the printing surface of the printing plate toward a given 15 surface, in order to locate all portions of the printing surface in the projection of the same surface, that is, in the same plane if the plate be a flat plate and into the same projection of a cylinder if the plate be a 20 curved plate.

The printing plate, especially the backing material thereof, is compressed by my improved device, preferably selectively according to the solidities of the printing portions 25 of the printing plate. Thus the portions of the printing plate at the printing portions thereof which are solid, are compressed to greater densities than those portions thereof which are provided with high-lights or intermediate solidities of printing surface. 30 These differences in densities are indicated in Fig. 4 by the differences in the closeness of the cross-sectional lines.

I accomplish the compressing operation 35 preferably by placing the printing plate, when a flat plate, with its printing face upon a plane hard surface, preferably of greater area than the area of the printing plate, as of a resistance member 40, which 40 may be a steel slab, all portions of which surface are in the same projection of a given surface, and providing a compressing member, exemplified at 41, preferably of greater area than the area of the printing plate, 45 which I apply to the backing surface of the printing plate, this compressing member being provided with hard contact faces acting upon the backing of the printing plate in equidistant relations throughout from the 50 hardened surface of the resistance member coacting with the printing surface of the printing plate.

Pressure is applied to cause approach between said compressing member and the 55 coacting resistance member, to compress the printing plate between said surfaces so as to cause compression of the printing plate, these hard contact faces preferably compressively acting upon the backing of the printing plate which, in practice, is usually softer or more readily compressible than the material of the printing surface of the printing plate, which is usually a printing shell. The printing surface is in any event supported 60 by the plane hardened surface of the resist-

ance member to prevent crushing thereof or injury thereto.

Protuberances and recesses are located at the back portion of the printing plate to aid in the compression of the printing plate. I prefer to employ a compressing member whose compressing surface comprises such protuberances and recesses, and in Figs. 4, 5 and 6 show such a member having protuberances having spaces therebetween. These protuberances or compressing areas are represented as elevations 43, between which there are depressions 44. These elevations preferably have sloping sides 45 forming the walls of the depressions, the sides sloping away from each other at the respective elevations, for contracting the depressions toward their bottoms preferably to appreciable extent, and the depressions are arranged to receive material of the 85 backing due to the entrance into the backing of the elevations. The materially sloping sides of the depressions react upon the material received in the depressions to cause compressing of those portions of the material of the backing received in said depressions. The sloping sides also afford relief for permitting ready removal of the compressing member after compression has taken place. The compressing member is 90 preferably a hardened steel plate.

One of the objects of providing the raised compressing faces and coacting depressions is to permit the compressing faces to compressingly act on the backing material 100 throughout the area of the same, and preferably to enter the backing material for exerting the compression, the materially sloping walls reacting with compressive pressure upon the backing material received in the depressions, thereby enhancing the compressive effect by employment of less pressures, and distributing the pressure throughout the printing plate, avoiding injury to the printing surface, and preventing spreading 105 of the printing plate in the direction of the plane of the plate, in order to maintain all printing lines of the printing surface in original relations in the directions of the plane of the plate to enable hair-line registry between printing plates of a set of plates, especially useful in so-called multicolor work.

A printing plate is in practice, during 110 the printing operation, subjected to greater pressures per area at the solid portions thereof, than it is at the other portions thereof, for instance, the high-light or light printing portions of the same. I therefore provide means whereby the backing of the printing plate at the solid portions thereof is caused to have greater density per area than the backing portions of the printing plate at the other portions thereof, for instance the high-light portions. 115

The compression may be accomplished by any suitable device capable of imparting substantially great pressures, for instance, a hydraulic press comprising a bed 48, on 5 which the resistance member 40 is received and upon which latter the printing surface of the printing plate is laid. (See Fig. 5.) This resistance member is preferably a hardened steel plate to resist all compression by 10 the printing plate and prevent injury to the printing lines of the printing plate. The compressing member provided with the compressing elevations and coacting depressions is placed upon the back of the printing plate, so as to coact with the backing material of the printing plate. A plunger 49 of the press coacts with the bed thereof, its presser surface and bed surface being equidistant from each other throughout their 15 areas, and the movable element, namely, the plunger, being guided, as by guides 50, as is usual in a press of this character, in true right lines perpendicular to such surfaces when applying the pressure. The applying 20 of the pressure causes the compression of the printing plate in manner hereinbefore described, and solidifies the same, including any soft or porous spots or portions therein.

I have shown the compressing elevations 25 as having square areas. Other forms of compressing elevations may be employed, or the compressing elevations may be connected with each other for forming disconnected depressions between said elevations, for instance as shown in Figs. 11 and 12, in which the compressing elevations are exemplified by the continuous elevated portions 51 having the depressions 52 therein, and sloping 30 walls 45.

I further prefer to employ compressing elevations of different areas and spacings according to the average solidities of the printing surface of the printing plate to be compressed, and prefer that the greater the 45 amount of solid areas there are in the printing plate, the greater shall be the proportion of compressing elevations in the compressing plate.

Thus, as examples, I have in Figs. 7 and 50 8 shown respectively a plan view and a cross-section of a portion of a compressing plate which I prefer to employ when operating upon printing plates having a large amount of solids in their printing surfaces. 55 Such plate may for instance have forty-five per cent of its area as elevation surface and fifty-five per cent of its area as depressions. The outer ends 46 of the elevations may be five thirty-seconds inch square and the sloping sides 45 have an inclination of sixty degrees.

In Figs. 4, 5 and 6, I have exemplified respectively a cross-section and a plan view 60 of a portion of a compressing member which I prefer to employ with a printing plate

having substantially balanced areas of solids and high-lights or intermediate conditions of solidities of printing surfaces, on which the area of compressing surface may amount to twenty-five per cent and the areas of depression to seventy-five per cent of the total area of the compressing member; and the outer ends 46 of the elevations be one-eighth inch square, and the sloping sides 45 have an inclination of sixty degrees. 70

I have in Figs. 9 and 10 illustrated respectively a plan view and a cross-section of an exemplified portion of a compressing member, which I prefer to employ for coacting with printing plates having a preponderance of high-lights, on which the areas of the compressing faces may be twelve per cent and of the depressions between the same eighty-eight per cent of the entire area of the compressing member, and the outer ends 80 46 of the elevations be three thirty-seconds inch square, and the sloping sides 45 have an inclination of sixty degrees. 85

All of the said elevations may have a height of one-twentieth of an inch, and the 90 bases of said sloping sides be spaced apart to provide the approximate areas mentioned. These examples are, however, exemplifications and not limitations, as the areas, proportions of area and inclinations may vary 95 within the spirit of my invention.

Further instancing desirable pressures to be employed in my improved device, and instancing a printing plate comprising an electro-deposited copper shell and a backing 100 composed of a cast backing metal, such as hereinbefore described, comprising lead, tin and antimony, it may be stated that I have found desirable pressures for instance upon a printing plate having a substantially solid 105 printing surface, and a size ten inches by twelve inches or one hundred and twenty square inches, to be a range of from one hundred and sixty tons to two hundred tons for the entire plate, equaling a range of 110 from substantially one and one-third tons per square inch of printing plate to one and two-thirds tons per square inch of printing plate; that when compressing such printing plates of the given size having a medium solidity of printing surface, aggregate pressures having a range of from eighty tons to one hundred and sixty tons pressure may be employed, representing 115 pressures having a range of from two-thirds of a ton per square inch to substantially one and one-third tons per square inch; and that when compressing said printing plates of such given size having a preponderance of light printing surface, aggregate 120 pressures having a range of fifty tons to eighty tons may be employed, representing a range of from five-twelfths of a ton per square inch to two-thirds of a ton per square inch of printing plate. It may be stated 125 130

further, that in employing my improved method on printing plates in which the backing material is very hard, I have found desirable pressures for instance upon a printing plate having a substantially solid printing surface, and a size of ten inches by twelve inches or one hundred and twenty square inches, to be a range of from three hundred and fifty tons to six hundred tons for the entire plate, equaling a range of from substantially three tons per square inch of printing plate to five tons per square inch of printing plate; that when compressing such printing plates of the given size having a medium solidity of printing surface, aggregate pressures having a range of from one hundred and fifty tons to three hundred and fifty tons pressure may be employed, representing pressures having a range of from one and a fourth tons per square inch to substantially three tons per square inch; and that when compressing such printing plates of such given size having a preponderance of high-lights, aggregate pressures having a range of from fifty to one hundred and fifty tons may be employed, representing a range of from substantially one-half to one and a quarter tons per square inch of printing plate. The medians of the respective ranges of pressures have been found suitable for the averages of said characters of plates. The pressures mentioned may vary according to the character of backing material and printing face employed, and are given as instances and not as limitations.

I have found, in printing plates, especially such as comprise printing shells of electro-deposited metal, and also in plates otherwise formed, that the edges or boundaries, as at 54, of printing surfaces are in practice higher or more prominent in unprepared printing plates than the printing surfaces, as at 55, between such edges or boundaries. Exemplifying this condition, I have found that, for instance, the dots in high-light areas, when subjected to highly magnified inspection, are really not dots, but are inclosing circles, the inner areas of which are sunken and either do not print or print very lightly, although to the naked eye they appear as fully developed dots.

By employment of my improved device, I am enabled to press the printing areas between boundary edges or lines into substantially the planes or projections of such printing boundaries or lines, so as to minimize the difference between such areas and said boundary edges or lines in printing for enhancing the printing effect. By means of my invention, I further bring all portions of the printing surface into the same projection of the same surface so as to minimize the necessity for overlaying and underlaying and producing highly efficient printing.

In subjecting the printing plate to the compressive actions hereinbefore described, I produce greater densities in the solid portions of the printing plate than in the high light portions of the same. In the high light portions of the printing plate there are greater areas in the printing face which are considerably depressed for avoiding printing thereof, and while all parts of the area of the printing plate are subjected to the same pressure in the compressive action upon the same, the pressures at the solid portions are resisted by greater areas of contact between the printing surface and the coacting resistance plate, upon which the same rests, than at the high-light portions of the printing plate, where greater unprinting areas are located.

These unprinting areas permit a portion of the metal being compressed to find relief in such unprinting areas, for causing less densities in the metal of the backing of the plate at those portions of the printing plate having more open areas in their printing surface than the solid portions thereof, this relief of density varying according to the solidities of the printing portions, the high-light portions being provided with the least densities. Forming the walls of the depressions of the compressing plate materially sloping in the manner hereinbefore described aids materially in accomplishing these results.

The relief of density mentioned is received in the unprinting depressions, which are in practice increased in depth, where necessary, as by routing or otherwise, in finishing the plate, but the distance of perpendicular yield of the bottom of these depressions toward the printing surface is slight. The distance of reception of the compressing faces into the plate may be instanced as one-tenth the thickness of the plate, although this distance may vary without departing from the spirit of my invention within the scope of the appended claims. The compressive action upon the plates in my improved device is preferably greater than any compressive action on said plate by any pressures to which the printing plate is subjected in the printing operation, to avoid compression of the printing plate during printing.

When printing from a plate made according to my improved device, therefore, those portions of the plate which are subjected to the greatest pressures per area in the printing operations are resisted by the greater densities in the printing plate, while those portions of the printing plate which are subjected to the less pressures per area in the printing operation, for instance, the high-light portions of the printing plate, are resisted by the portions of the printing plate of less density, providing resistances in the printing plate proportional to the printing

pressures per area required for proper printing of the various printing portions of the plate.

When the printing plate has been compressed, the backing surface thereof will have the form of the compressing face of the compressing member impressed therein, for instance forming ridges 57, as shown in Figs. 4 and 13. I therefore bring the printing plate to uniform thickness at its printing portions by removing the ridges in the backing surface thereof, for instance, by employment of a shaving machine, as hereinbefore mentioned, to take a shaving or shavings off of the backing of the same, to remove the undesirable ridges therein, and reduce the printing plate to uniform thicknesses at its printing portions.

The compressing member may if desired be arranged in curved form and means provided whereby the printing plate in curved form may be compressed.

Thus I have in Figs. 14 to 20, inclusive, illustrated an exemplifying machine by means of which compression of curved printing plates may be obtained.

In this exemplification, there is a bed 61, which has a supporting face 62, and serves as the resistance member for the printing plate, preferably of greater area than the area of the printing plate and harder than the printing face with which it is to coact, and preferably formed on the sector of a cylinder having the diameter of the path of the printing surface of the printing plate while printing. The curved printing plate, represented at 24, is laid on this curved surface, with its printing face toward said surface. Pressure is applied for causing the printing surface to intimately contact this curved surface so as to locate the printing surface in the projection of the sector of its proper cylinder.

The backing of the cylinder is then compressed, preferably on lines substantially perpendicular to the printing surface, or by pressures directed radially of said surface, and preferably in manner to maintain the distance relations, in the projection of the printing surface, between the printing lines of said surface, in order to maintain the registry function of the printing plate. I have exemplified this as accomplished by means of compressing faces having compressing elevations 66, having sloping sides 45, and depressions 67, similar to the elevations 43 and depressions 44 of the compressing member 41, except that in this case, the compressing member, represented generally at 68, is arranged on the sectors of a cylinder for coacting with the curved surface at the back of the curved printing plate.

The sides 45 slope materially for substantially contracting the depressions toward their bottoms, whereby said sloping sides of

the depressions react upon the material received in the depressions to cause compressing of those portions of the material of the backing thus received in said depressions, as explained with reference to the compressing faces and sloping walls employed in compressing flat plates.

I have shown these compressing elevations arranged on compressing plates 70, suitably secured to compressing bodies 71, as by a tongue and groove joint 72 between the same, or the compressing plate and its body may be formed as an integral structure. The compressing plates are preferably hardened steel plates. The respective compressing plates and their respective bodies compose sectors of the compressing member 68, which are arranged to be moved radially with relation to the curved printing plate. In arranging the compressing faces with relation to the sectors of the compressing member, I prefer that the depressions between elevations be coincident with the lines of separation between the sectors.

An exemplification of means for causing the compressing movement may comprise a ram 75, moved in a guide 76, in a frame 77 of the machine, and having wedge faces 78 thereon, arranged as sectors of frusto-cones, which coact with complementary wedge faces 79 on the sectors of the compressing member. Any suitable means may be provided for operating the ram. I have shown the same as provided with a screw 80, with which a nut 81 is threaded, the nut being shown as in the hub of a gear 82. The nut is prevented from moving endwise but is permitted to rotate.

A pinion 83 meshes with the gear. The pinion is on a shaft 84 journaled in bearings 85 on the frame, and having a hand-wheel 86 thereon for operating the same.

The sectors of the compressing member are provided with radially arranged guides 87, which are guided in guideways 88, in aprons 89, 90, of the machine frame, the sectors being guided in similar paths at their respective ends. The sectors may at that end thereof toward which the ram moves be provided with extensions 91 and additional guides 92 slidable in guideways 93. The respective sectors are at each end thereof provided with a lug 94, a spring 95 between said lug and a ledge 96 on the apron, normally urging the sector toward its operating part and normally urging separation between the compressing member and the curved plate.

Means are provided for ready reception of the plate between the bed or resistance member and the compressing member, which is exemplified as accomplished by raising and lowering the bed, as by means of guiding the bed in guides 98 in the frame, and providing eccentrics 99, fixed to shafts 100, journaled in bearings 101 of the frame, two

of these shafts being shown. The eccentrics act on contact faces 97 on the bed. Arms 102 are fixed to the shafts. A link 103, articulated at 104 with the arms, connect 5 the arms for combined movements. One of these arms may be extended as a handle 105.

Movement of the bed toward the compressing member is preferably limited by 10 stops 106 to locate the curved face of the bed at such point, so that it lies in the sector of the cylinder on which the plate has been curved, or which is coincident with the cylindrical path of the printing plate during 15 the printing operation, and to locate this sector at such distance from the frusto-cones of the ram, so that the axes of these frusto-cones and said sector will be coincident. This movement also preferably causes 20 intimate contact between the rear face of the backing of the printing plate and the compressing member to arrange the printing plate on its true curvature.

The radial movements of the sectors of 25 the compressing member are substantially perpendicular to the various portions of the printing plate with which said sectors coat, the compressing face of said sectors being of such construction as to maintain the 30 printing plate as a whole to its original dimensions and to maintain the distance relations, in the projection of the printing surface, of the printing lines of said surface, as hereinbefore explained with relation to 35 the compression of flat plates.

The action and results of compression and solidification of the curved plate are the same as heretofore explained in connection 40 with the compression of flat plates. The portions of the curved printing plate comprising solid printing areas are compressed to greater density than the portions of the plate at which lighter printing surfaces are located. Compressing faces having various 45 shapes and areas may also be employed in compressing curved plates, as explained in relation to compressing flat plates.

It is obvious, of course, that other means 50 may be employed for causing approach and recession between the curved printing plate and the compressing member or for causing compression of the curved printing plate, within the spirit of my invention and the scope of the appended claims.

55 The rear face or backing of the curved printing plate has the ribs or projections, due to compression, removed, as by shaving, for instance, by employment of the shaving machine hereinbefore referred to.

60 The marginal bearers 25 are also preferably trimmed from the plate, whether flat or curved, for instance, in the line of the grooves 26 between said bearers and the printing surface, and the edge of the plate 65 provided with a suitable attaching face for

securing the plate to the plate cylinder or to a supporting block by any ordinary or well-known means.

If the printing plate be provided with 70 portions which must be removed from the printing side prior to printing the plate, for instance, interior bearers, such removal is accomplished, as by routing. The printing plate may, if desired, be subjected to additional refinements, provings and corrections, 75 as explained in my aforesaid pending application, of which this is a division, but my improved device may be employed without such steps and refinements, and produce a highly improved printing plate.

80 The printing plate, whether flat or curved, may be instanced to be three-sixteenths of an inch thick in its finished state, but the diameters and dimensions given are merely exemplifications, and may be altered or changed, or other diameters and dimensions substituted, within the spirit of my invention and the scope of the appended claims.

85 By means of my improved device a printing plate is obtained having a printing surface, the printing lines of which are located in the projection of the same surface, that is the same plane, if it be a straight plate, and the same surface of a cylinder or sector of a cylinder if the plate be a curved plate, as determined by print pressures. In printing from a printing plate operated on by my improved device, the tympan surface upon which the sheets of paper or other material being printed are laid in the printing operation, may also be in the projection of a given surface, either plane or cylindrical, and be 90 comparatively hard, so that the printing contact between the paper being printed and the printing plate compressed by my improved device, is what may be termed a kiss contact between the paper and the ink for transferring the pigments of ink to the paper, and all rubbing contact between the paper and the ink which is incident to causing the paper to be received in depressions or causing the paper to be bent over bulges in the faces of make-readies as now generally employed, may be avoided.

95 Having thus fully described my invention, what I claim as new, and desire to secure by Letters Patent, is:

1. In compressing means for printing plates having different preponderances of solidities of printing portions in their printing surfaces, said compressing means having elevations and depressions having different areas in accordance with said different preponderances of solidities of printing portions in said printing surfaces.

100 2. In compressing means for printing plates respectively having differences of solidities of printing portions in their printing surfaces, the combination of a resistance member, and coacting compressing members

- respectively having elevations and depressions having different areas in accordance with the respective differences of solidities of said printing portions in said printing surfaces.
3. In compressing means for compressing printing plates having different preponderances of solidities of printing portions in their printing surfaces, the combination of a supporting member, coacting compressing members, said printing plates, the latter arranged to be received between said supporting member and said coacting compressing members, said last-named members and said printing plates having a surface between them provided with elevations and depressions having different areas in accordance with said different preponderances of solidities of printing portions in said printing surfaces, and means causing approach between said compressing members and said supporting member for compressing said printing plates.
4. In compressing means for compressing printing plates respectively having differences of solidities of printing portions in their printing surfaces, the combination of a supporting member, coacting compressing members respectively having elevations and depressions having different areas determined by the respective differences of solidities of printing portions in said printing surfaces, and means for causing approach between said members.
5. In compressing means for compressing printing plates respectively having differences of solidities of printing portions in their printing surfaces, the combination of a supporting member, coacting compressing members respectively having elevations and depressions having different areas determined by the respective differences of solidities of printing portions in said printing surfaces, means for causing approach between said members, and resilient means causing separation between said members.
6. In compressing means for compressing curved printing plates having different preponderances of solidities of printing portions in their curved printing surfaces, the combination of a plurality of compressing means respectively having curved compressing surfaces provided with elevations and depressions having different areas in accordance with said different preponderances of solidities of printing portions in said curved printing surfaces.
7. In compressing means for compressing curved printing plates respectively having differences of solidities of printing portions in their curved printing surfaces, the combination of a curved resistance member and coacting curved compressing members respectively having elevations and depressions having different areas in accordance with the
- respective differences of solidities of said printing portions in said curved printing surfaces.
8. In compressing means for curved printing plates respectively having different preponderances of solidities of printing portions in their curved printing surfaces, the combination of a plurality of curved compressing parts respectively divided into sectors, said respective curved compressing parts having curved compressing surfaces having elevations and depressions having different areas in accordance with the different preponderances of solidities of printing portions in said respective curved printing surfaces.
9. In means for compressing curved printing plates having differences in printing effects of different printing portions in their printing surfaces, the combination of a supporting member, and coacting compressing members respectively having elevations and depressions determined by the respective differences in printing effects of said different printing portions.
10. In compressing means for compressing curved printing plates having differences in the printing effects of different printing portions in their printing surfaces, the combination of a supporting member, and coacting compressing members respectively having elevations and depressions having different areas determined by the respective differences in said printing effects.
11. In compressing means for compressing curved printing plates having differences in printing effects in different printing portions of their printing surfaces, the combination of a supporting member having a supporting face arranged on the sector of a cylinder, and coacting compressing members respectively having compressing faces which vary in accordance with the differences in printing effects of said different printing portions, said compressing faces arranged as sectors of cylinders substantially concentric with said first-named sector.
12. A compressing means for a curved printing plate comprising a compressing member including a plurality of compressing parts having curved compressing faces and means causing relative compressing movement between said compressing parts.
13. A compressing means for a curved printing plate comprising a resistance member having a curved resistance face arranged thereon, a compressing member having a curved compressing face coacting with said curved resistance face, and forming a pair of members, a member of said pair of members arranged in sectors, and means for moving said sectors toward the other of said members.

14. In compressing means for a curved printing plate having an outer curved printing surface, the combination of a pair of curved opposed members between which said curved printing plate is arranged to be received, there being a surface provided with indentations and depressions between the body portions of said inner curved member and of the backing of said printing plate, and means for causing approach between said members in a plurality of directions. 70
15. In compressing means for a curved printing plate having an outer printing surface, the combination of a pair of curved opposed inner and outer members between which said curved printing plate is arranged to be received, there being a surface provided with indentations and depressions between the body portions of said inner member and said printing plate, said inner member comprising a plurality of parts, and means for causing approach of the parts of said inner member toward said outer member by substantially radial forces. 75
16. In means for compressing a curved printing plate having an outer printing surface, the combination of a curved support for said outer printing surface, and a compressing member comprising a plurality of parts arranged to act upon the inner surface of said curved printing plate in a plurality of directions. 80
17. In means for compressing a curved printing plate having an outer printing surface, the combination of a curved support for said curved printing surface, an inner member comprising sectors having faces provided with elevations and depressions coacting with the inner backing portion of said curved printing plate, and means for causing the movement of said sectors toward said curved support in substantially radial lines. 85
18. In means for correcting a curved printing plate having an outer printing surface, the combination of substantially concentric surfaces between which said curved printing plate is arranged to be received, and means for causing approach between said surfaces in a plurality of substantially radial paths. 90
19. In means for correcting a curved printing plate having an outer printing surface, the combination of curved surfaces between which said curved printing plate is arranged to be received, and means for causing approach between said curved surfaces in a plurality of directions, there being elevations and depressions at the inner one of said surfaces, and the said elevations arranged to be pressed into said backing by said approach between said surfaces. 100
20. In means for correcting a curved printing plate having an outer printing surface, the combination of curved surfaces between which said curved printing plate is arranged to be received, and means for causing approach between said surfaces in a plurality of directions, there being elevations and depressions at the inner one of said surfaces, the said elevations arranged to be received, there being a surface provided with indentations and depressions between the body portions of said inner curved member and of the backing of said printing plate, and means for causing approach between said members in a plurality of directions. 105
21. In compressing means for printing plates, the combination of a curved resistance member, a curved compressing member, a printing plate arranged to be received between said curved members, said curved compressing member and said printing plate having coacting surfaces including elevations and depressions, and means for causing approach between said members comprising compressing sectors. 110
22. In compressing means for printing plates, the combination of a curved resistance member and a curved compressing member, the printing plate arranged to be received between said curved members, means for causing approach between said members comprising compressing sectors, means for moving said sectors in substantially radial lines, and resilient means for retracting said sectors. 115
23. In compressing means for compressing curved printing plates, the combination of a resistance member having a curved resistance surface for the printing plate, a curved compressing member comprising sectors, means for causing movement of said resistance member toward said compressing member, and means causing movement of said sectors toward said resistance member. 120
24. In compressing means for compressing curved printing plates, the combination of a resistance member having a curved resistance face for the printing plate, a compressing member comprising sectors, means for guiding said sectors in radial lines, and operating means for said sectors, said operating means and said sectors comprising complementary wedge faces. 125
25. In compressing means for compressing curved printing plates, the combination of a resistance member having a curved resistance face for a printing plate, a compressing member comprising sectors, means for guiding said sectors in radial lines, a ram, said ram and said sectors provided with complementary moving faces, and means for moving said ram lengthwise of said sectors. 130
26. In compressing means for compressing curved printing plates, the combination of a resistance member having a curved resistance face for a printing plate, a com-

pressing member comprising sectors, means for guiding said sectors in radial lines, a ram, said ram and said sectors provided with complemental moving faces, means for 5 moving said ram lengthwise of said sectors, and resilient means for retracting said sectors.

27. In compressing means for compressing curved printing plates, the combination 10 of a resistance member having a curved face for the curved printing surface of the printing plate, a compressing member comprising sectors, means for moving said resistance member toward and from said compressing member, a ram at the inner ends of said sectors, said ram and said sectors comprising complemental wedge faces, a rotating operating part for said ram, and threaded means between said rotating operating part and 15 said ram for moving said ram lengthwise of said sectors upon rotation of said rotatable operating part.

28. In compressing means for compressing curved printing plates, the combination 20 of a resistance member having a curved surface for the curved printing plate, a compressing member comprising sectors, radial guides for said sectors, means for compressingly moving said sectors lengthwise of said 25 guides toward said resistance member, and

means for resiliently retracting said sectors along said guides, and means for moving said resistance member toward and from said compressing member.

29. A compressing member for compressing a curved printing plate comprising sectors having elevations and depressions arranged substantially on the sector of a cylinder and having sloping walls between them to form said depressions contracting toward 40 their bottoms in manner to react with pressure upon the inner wall of the curved printing plate during compressing of said curved printing plate, and means for moving said sectors in different radial paths. 45

30. A curved compressing member for compressing a curved printing plate comprising elevations and depressions arranged substantially on the sector of a cylinder, said elevations arranged to enter the inner face 50 of the curved printing plate, and means for causing movement of different portions of said compressing member in different paths.

In testimony whereof, I have hereunto signed my name in the presence of two sub- 55 scribing witnesses.

LESLIE W. CLAYBOURN.
